UNITED STATES PATENT OFFICE.

WILLIAM G. SEARS, OF CHATTANOOGA, TENNESSEE.

RAIL-TIE.

SPECIFICATION forming part of Letters Patent No. 444,910, dated January 20, 1891.

Application filed April 16, 1890. Serial No. 348,147. (No model.)

To all whom it may concern:

Be it known that I, WILLIAM G. SEARS, a citizen of the United States, residing at Chattanooga, in the county of Hamilton and State 5 of Tennessee, have invented certain new and useful Improvements in Rail-Ties; and I do hereby declare the following to be a full, clear, and exact description of the invention, such as will enable others skilled in the art to 10 which it appertains to make and use the same.

This invention relates to an improvement in cross-ties for railways, the object being to provide a more perfect metallic cross-tie or sleeper which may afford a yielding elastic or 15 cushioned seat for the rail, thus obviating the constant pounding incident to the use of the ordinary railway construction, and especially characteristic of inelastic ties of solid iron or steel, which results speedily in the injury and 20 destruction of the rails and ties; and the invention consists, essentially, in the combination, construction, and arrangement of parts, substantially as will be hereinafter described and claimed.

25 In the annexed drawings, illustrating my invention, Figure 1 is a perspective view of my improved rail-tie. Fig. 2 is a side elevation of a railway-rail supported upon my improved tie to which it is secured, the tie being shown in transverse section on the line $x-x$ of Fig. 3. Fig. 3 is an enlarged detail plan view showing one of the transverse rail-supporting spring-plates and the rail secured thereon by a track-fastener. Fig. 4 is an enlarged partial perspective view of my improved metallic tie, showing certain details 35 of its construction.

Similar letters of reference designate corresponding parts throughout all the different 40 figures of the drawings.

My improved hollow metallic rail-tie is made in the form of a hollow trough, gutter, box, or receptacle, of steel or other metal of suitable strength and thickness and having 45 a proper length to adapt it for being placed in the ballast of the road-bed, like the ordinary tie, A denoting its bottom, and $A'A'$ its sides, which are preferably inclined outwardly, the upper edges of these sides $A'A'$ being provided 50 with horizontal flanges $a a$, which are notched or indented at $a'a'$ near each end, where the transverse rail-supporting plates

are to be secured upon the tie-box. In Fig. 2 the hollow trough is seen embedded in the ballast of the road-bed, which is firmly pressed 55 around it in such a manner that the flanges $a a$ are on a level with the surface of the bed or at a trifling distance above it.

Secured upon the open tie or sleeper box, near each end thereof, at points where the 60 rails cross the tie, and serving to support the latter, are flat elastic plates $B B$, preferably made of spring-steel and having a convenient and suitable thickness and width. These 65 plates are preferably arched, curved, or rounded, so as to be somewhat higher at the middle than at the ends. They are secured to the tie in some suitable manner. A preferable way of securing them is to provide them at the ends with bends or inturned 70 flanges b , which form grooves to receive the flanges a on the tie, and also with a convenient number of projections b' struck up from said flanges (see Fig. 2) and adapted to enter the notches $a'a'$ in the horizontal tie-flanges $a a$. 75 Other modes of connecting the spring-plates may doubtless be devised and substituted for that here described with good effect.

C denotes a section of a rail that rests upon my improved tie, it being shown for the purpose of more clearly explaining the invention. This rail is secured upon the supporting-plate by some strong track-fastening, such as that described in my pending application for patent, filed March 15, 1890, Serial No. 343,983, 80 and consisting, essentially, of a fixed clamp c , acting on the inner flange of the rail, an outer bar d , having a doubly-inclined face, a brace-block having an inclined face and with one side pressing against the object, and 85 an interposed wedge f between the outer bar and the brace, said wedge having its wedging-faces each doubly inclined, and the inner clamp, outer bar, and brace-block being fixed in slots in the rail-supporting plate B , as 90 shown.

Having thus described my invention, what I claim as new, and desire to secure by Letters Patent, is—

1. The combination of the hollow tie-box 100 having its sides provided with horizontal flanges, the transverse spring rail-supporting plates having projections at the ends adapted to enter notches in the horizontal flanges, and

track-fastenings on said plates for securing the rails thereon, substantially as described.

2. The combination of the hollow tie-box having its sides provided with horizontal flanges, transverse rail-supporting spring-plates fastened thereon, and track-fastenings on said plates for securing the rails thereon, substantially as described.

3. The combination of the hollow tie-box having its sides provided with horizontal flanges having notches, the transverse rail-

supporting spring-plates having the bends at each end, and the struck-up projections adapted to enter the notches in the horizontal flanges, substantially as described.

In testimony whereof I affix my signature in presence of two witnesses.

WILLIAM G. SEARS.
